[57] **CLAIM**

The ornamental design for a housing for the base of a cordless telephone with speakerphone, as shown and described.

DESCRIPTION

FIG. 1 is a top-front perspective view of the housing for the base of a cordless telephone, with speakerphone, and including a broken line showing of a handset in a cradled position, showing my new design;

FIG. 2 is a front elevational view of the housing for the base of a cordless telephone with speakerphone of FIG. 1;

FIG. 3 is a top elevational view thereof;

FIG. 4 is a bottom elevational view thereof;

FIG. 5 is a rear elevational view thereof;

FIG. 6 is a right side elevational view thereof; and,

FIG. 7 is a left side elevational view thereof.

The broken line showing of a handset in FIG. 1 is for environmental purposes only and forms no part of the claimed design.

FIG. 2

FIG. 3

FIG. 4

FIG. 5

FIG. 6

FIG. 7
